EUGENE O. GOLDBECK, OF SAN ANTONIO, TEXAS

CONTROL MECHANISM FOR PANORAMIC CAMERAS

Application filed April 16, 1929. Serial No. 355,572.

This invention appertains to improvements in panoramic cameras, and has for its main object to provide a governor mechanism for controlling the operation of the actuating motors of such cameras, whereby to secure a much slower speed of movement of a camera and the film within the same for correspondingly increasing the time period of exposure of the film for the making of photographs out of doors in cloudy or inclement weather, or within interiors where ordinarily sufficient light is not to be obtained or provided, than has heretofore been possible of attainment in known types of such motor governor mechanisms.

With the foregoing and other equally important objects and advantages in view, the invention resides in the certain new and useful combination, construction and arrangement of parts, as will be hereinafter more fully described, set forth in the appended claims, and illustrated in the accompanying drawings, in which:

Figure 1 is a fragmentary front elevation of the rear detachable portion of the casing of a conventional form of panoramic camera, showing a practical embodiment of the auxiliary governor mechanism as it appears in its cooperative relation with the usual governor mechanism of the camera.

Figure 2 is a vertical longitudinal section taken on the line 2—2 of Figure 1.

Figure 3 is a horizontal section taken on the line 3—3 of Figure 2, and

Figure 4 is an enlarged fragmentary section through a portion of the frame of the usual governor mechanism, showing the manner of the journalling therein of an end of the shaft of the auxiliary governor mechanism.

Referring to the drawings, wherein like characters of reference designate corresponding parts in the several views thereof, the casing part of a standard form of camera, as shown therein, comprises a back wall 10, an outer side wall 11, an inner partition wall 12, and a bottom wall 13.

As shown in Figure 2, the bottom wall 13 is formed of spaced inner and outer wall sections 14 and 15 respectively, to house within

the space between the same the usual train of gears (not shown) connecting the standard form of governor device 16 at the left-hand side of the inner partition wall 12, with the usual spring motor (not shown) located at 55 the opposite side of the latter.

The motor is generally mounted within the casing part at the lower end of a film winding drum (not shown), and a shaft connection (not shown), driven from the gearing train, 60 depends from the bottom wall 13 for geared connection with a stationary gear mounted in horizontal position on the upper end of a tripod, or other suitable support (not shown) 65 of the camera.

The shaft 17 of the usual governor device 16 has its lower end journaled in the bottom wall 13 of the casing part, and its upper end in the end plate 18 of the supporting frame 19, the latter being secured in position to and 70 at the inner side of the inner bottom wall section 14.

In carrying out the objects and purposes of the present invention, an auxiliary governor device 20 is provided, and has the lower end of its shaft 21 journaled in a bore or recess 22 opening outwardly of the upper face of the frame plate 18, and is supported on a ball bearing 23 disposed therein, substantially as is shown in Figure 4. The upper end of the shaft 21 is journaled through a bracket 24 secured against the inner side 80 of the back wall 10 of the casing.

Mounted on the end of the shaft 17 of the ordinary governor 16, which projects upwardly from the end plate 18 of the supporting frame 19, is a gear 25. This gear is disposed in mesh with a pinion 26 secured on the adjacent end of the shaft 21 of the auxiliary governor device 20. This gear 25 is 85 preferably connected to the shaft 17 by means of a cotter pin or the like 27 when operative, which pin is passed through aligned openings formed diametrically through the hub portion of the gear 25 and the engaged end of the shaft 17, but is to be disconnected from the shaft by the removal of the cotter pin 27 in the use of the ordinary governor mechanism 16 only.

Secured on the upper end portion of the

governor shaft 21 inwardly of the bracket 24 is a brake disk 28, with which a friction brake element is cooperative. This element is carried at the upper side of an angular 5 extension 29 formed at the lower end of an actuating bar 30, which is slotted, as at 31, for sliding engagement on a supporting member or screw 32, the latter being secured in the inner surface of the outer side wall 11 10 of the camera casing, and has its extreme upper end pivoted, as at 33, to an intermediate point on a movable index arm 34.

This index arm 34 is pivoted toward its inner end, as at 35, to the inner face of the 15 side wall 11 of the casing part, while the outer end of the same is arranged to overlie a graduated scale member 36 also secured to the inner face of the side wall 11 aforesaid, and is pointed at this end to accurately register with 20 the graduations on the scale member 36 when moved to the selected position of adjustment of the brake element, relative to the brake disk 28. A finger piece 37 is secured to one end, preferably the index end as shown, of 25 the index arm 34 to facilitate the manipulation of the same, and a pair of stops 38 and 38' are arranged to limit the movement of the index arm at each of the opposite ends of the scale member 36.

30 To allow for the mounting of the auxiliary governor device 20 within the casing part of a standard form of camera, the side wall 11 thereof is recessed, as at 39, to permit of the necessary operative movements of the 35 weights on the several supporting arms of the device, and this recess may extend entirely through the wall 11, except for the outer leather or fabric covering with which the usual forms of cameras are entirely 40 cased.

In the operation of standard forms of panoramic cameras it has been found that in the use of the governor mechanisms ordinarily employed to control the rate and uniformity of speed of the camera and film operating motors, it is practically impossible to so adjust or move such mechanisms as to reduce the speed of the motor to that or below that required for the operation of the camera and 45 film for the taking of pictures on extremely cloudy or stormy days, and in interiors where the light is poor, and it is impossible to provide proper artificial light, but, by adding the auxiliary governor mechanism to the 50 present governor mechanism, the desired results can be successfully obtained.

In effecting any modification of the governor mechanisms as usually provided in standard makes of panoramic cameras, it has 55 also been found that, while in certain instances, a reduction in speed of operation of the actuating motor has been obtained, the revolving movement of the camera on its support or tripod and the feed of the film strip 60 is not uniform, and more or less jerky, de-

pending upon the magnitude of modification made in the said mechanisms. This is not true of the operation of the motor when the auxiliary governor mechanism is employed in cooperation with the usual governor mechanism, but to the contrary, the camera and film are revolved and fed in a smooth and uniform manner, such as allows for the making of photographs with a properly determined time exposure, in cloudy or stormy 70 weather, or in darkened interiors, equal to those made under the most ideal natural or artificial light conditions.

Without further description, it is thought that the features and advantages of the invention will be readily apparent to those skilled in the art, and it will of course be understood that changes in the form, proportion and minor details of construction 80 may be resorted to, without departing from 85 the spirit of the invention or its scope as claimed.

Having thus fully described the invention, what is claimed is:

1. The combination of a main speed control governor mechanism of the actuating motor of a panoramic camera, and an auxiliary governor mechanism directly coupled thereto to effect a reduction of the operating speed of the motor beyond that of the lowest 90 motor speed obtainable in the use of the main governor mechanism alone.

2. The combination with a main speed control governor mechanism of the actuating motor of a panoramic camera, of an auxiliary 100 governor mechanism cooperative therewith to effect a reduction of the operating speed of the motor beyond that of the lowest motor speed obtainable in the use of the main governor mechanism alone, and means for connecting and disconnecting said auxiliary governor mechanism directly to and from the said main governor mechanism.

3. The combination with a main speed control governor mechanism of the actuating motor of a panoramic camera, of an auxiliary 110 governor mechanism directly coupled thereto to effect a reduction of the operating speed of the motor beyond that of the lowest motor speed obtainable in the use of the 115 main governor mechanism alone, and means for regulating said auxiliary governor mechanism to vary the reduced operating speed of the motor.

4. The combination with a main speed control governor mechanism of the actuating motor of a panoramic camera, of an auxiliary 120 governor mechanism cooperative therewith to effect a reduction of the operating speed of the motor beyond that of the lowest motor speed obtainable in the use of the main governor mechanism, means for selectively regulating said auxiliary governor mechanism to vary the reduced operating speed of the motor, and means for connecting and disconnecting 125 and discon-

necting said auxiliary governor mechanism to and from the said main governor mechanism.

5. The combination with a main speed control governor mechanism of the actuating motor of a panoramic camera, of an auxiliary governor mechanism cooperative therewith to effect a reduction of the operating speed of the motor beyond that of the lowest 10 motor speed obtainable in the use of the main governor mechanism alone, a brake mechanism cooperative with said auxiliary governor mechanism, and means for selectively varying the braking effect of said brake 15 mechanism, whereby to vary the reduced operating speed of the motor.

6. The combination with a main speed control governor mechanism of the actuating motor of a panoramic camera, of an auxiliary 20 governor mechanism cooperative therewith to effect a reduction of the operating speed of the motor beyond that of the lowest motor speed obtainable in the use of the main 25 governor mechanism alone, a brake mechanism cooperative with said auxiliary governor mechanism, an index arm for actuating said brake mechanism to vary the braking effect thereof, whereby to correspondingly vary the reduced operating speed of the motor, and 30 a scale cooperative with said index arm, said scale being graduated in different values of operating speed of the motor and correspondingly for different time periods of exposure required for the camera under varying light 35 conditions.

7. The combination with a main speed control governor mechanism of the actuating motor of a panoramic camera and including the supporting frame of the governor mechanism, of an auxiliary governor mechanism disposed at one side of the center of one end 40 of the said frame, the operating shaft of said auxiliary governor mechanism having its lower end journaled in a bearing opening 45 formed in the opposed end of said frame, a ball bearing seated within said bearing opening and supporting the said governor shaft, and means for operably connecting both of 50 said governor mechanisms together.

8. The combination with a main speed control governor mechanism of the actuating motor of a panoramic camera and including the supporting frame of the governor mechanism, of an auxiliary governor mechanism disposed at one side of the center of one end 55 of the said frame, the operating shaft of said auxiliary governor mechanism having its lower end journaled in a bearing opening 60 formed in the opposed end of said frame, a ball bearing seated within said bearing opening and supporting the said governor shaft, means for operably connecting both of 65 said governor mechanisms together, and 70 means for connecting and disconnecting said

auxiliary governor mechanism to and from the said main governor mechanism at will.

9. The combination with a main speed control governor mechanism of the actuating 70 motor of a panoramic camera and the supporting frame of the governor mechanism, of an auxiliary governor mechanism supported by the frame and having an operating shaft journaled in the frame, and means for operably connecting said governor mechanisms, whereby they will jointly function to control the speed of the motor uniformly through a range below that to be obtained in the use of the main governor mechanism 75 alone.

10. The combination with a panoramic camera including a main speed control governor mechanism for the actuating mechanism thereof, and an auxiliary governor mechanism housed within the casing of the 80 camera and adapted to be operatively coupled to the main governor mechanism to effect a more uniform speed of the motor at ranges thereof below that to be obtained in the use of the main governor mechanism 85 alone.
